COIL HANDLING APPARATUS

Edward M. Chandler, Alcoa, Tenn., and Peter J. Castora, Pittsburgh, Pa., assignors to Aluminum Company of America, Pittsburgh, Pa., a corporation of Pennsylvania

Application November 13, 1941, Serial No. 418,940

16 Claims. (Cl. 242—81)

This invention relates in general to apparatus for handling material in web, strip, and coil form, and it is directed more particularly to apparatus for removing or stripping coiled strip metal from a collapsible reel or drum, but the invention as a whole, as well as various features thereof, is suitable also for use in various other relations wherein handling of coils rapidly and without damage thereto or to the metal surfaces is a primary consideration.

One object of the invention is to provide coil handling and transferring apparatus of improved form with respect to the manner in which the coils are transferred from one axial coil support to another. Another object of the invention is the provision of cooperative coiling and unloading mechanism for strip metal, whereby a tight wound coil which requires tying to prevent unwinding may be removed from the winding mandrel immediately upon completion of the coiling operation without the necessity of first tying the coil. Another object is to provide an improved form of mechanism for engaging and stripping coiled strip metal from a winding reel, wherein the stripping mechanism may be brought into operative relation with the strip metal before completion of the coiling operation, in order to restrain the end portion of the strip and to maintain the coil in its tight wound condition throughout the stripping operation, and whereby tying of the coil is effected subsequent to stripping thereof. A further object is to provide means for preventing the inside wraps or turns of the coil extending telescopically during the reel unloading operation. Still another object is to provide an apparatus that is especially adapted for handling highly finished strip metal in a manner affording maximum protection to the metal and its surface finish. A still further aim of the invention is the provision of a strip reel unloader of generally simplified and rugged construction and of improved operating characteristics and efficiency whereby the unloading time actually required to remove a coil from the reel with careful handling is materially shortened, and which enables the reel to be put into service for reeling a subsequent strip independently of the return of the unloader to position for unloading the subsequent strip. These and other objects of the invention will become clear from a perusal of the detailed description thereof taken in conjunction with the accompanying drawings illustrating a satisfactory embodiment of the invention, wherein

Fig. 12 is a cross sectional view taken on the line XII—XII of Fig. 2 on an enlarged scale, but showing the presser device in coil holding or clamping position.

In general, the apparatus comprises a reciprocable device or car that is disposed under the drum or mandrel of the coiling mechanism and is movable lengthwise thereof so as to move a coil from the mandrel onto a swinging coil gate that is normally positioned in longitudinal alignment with the axis of the mandrel. A vertically movable coil support is mounted on the car for movement into and out of supporting engagement with the lower periphery of the coil, and cooperating therewith is an overhanging coil presser member or clamping device that is movable into and out of engagement with the upper periphery of the coil. In the simplest structural arrangement, the overhung holding device is mounted vertically opposite the coil support on a vertically swingable arm that is journalled on an upright portion of the car. A link connection is provided between the swinging arm

40 and an operating lever that is pivoted on the carriage and also connected to the coil support, the connecting arrangement being such that the holding device and the coil support are moved in opposite directions by the latter and when

45 moved toward each other are adapted to clamp

50 and an operating lever that is pivoted on the carriage and also connected to the coil support, the connecting arrangement being such that the holding device and the coil support are moved in opposite directions by the latter and when

55 moved toward each other are adapted to clamp

a coil therebetween and firmly hold the coil turns against self-unwinding movement. Provision is made to bring the holding device into cooperative relation with the strip material during the coiling operation and impose a predetermined holding force on the coiled strip thereby, in order to prevent unwinding of the tensioned strip in the coil as the tail end of the strip leaves the mill rolls, to restrain flapping of the end of the strip during stopping of the reel, and to hold the coil against self-unwinding during the unloading operation. As soon as the coiling operation is completed, the mandrel is collapsed so that the coil is then supported by the lower coil support and the unloading operation is initiated by actuation of the carriage traversing means without delaying to tie or wire the coil. To prevent the coil extending telescopically in cases where a mandrel having a limited collapsing movement is used, a reciprocable stripper bar is provided to effect unitary traveling movement of the stripper and the carriage at the same rate after the stripper engages the coil. In addition, means are provided to effect immediate return of the stripper to normal position independently of return of the carriage so that rolling and coiling of the next strip may proceed while the stripped coil is being tied and removed from the coil gate, after which the car is returned to its coil receiving position under the winding drum.

Referring now more particularly to Figs. 1, 2, and 3, mechanism is provided for taking up strip metal under tension from a strip reducing mill, indicated generally by the numeral 10, the strip being indicated by the numeral 11. This strip as it leaves the mill 10 is wound into a compact coil 12 upon a power driven reel or drum structure 13, the reel being of the expandable and collapsible type well known in the art in order to facilitate removal of the coil. The reel is mounted on the outer end of a power shaft 14 that is carried by bearings 15, only one of which is shown, in a drive frame 16. The shaft, and consequently the reel, may be driven by any suitable gearing or driving mechanism (not shown), and for stopping the reel at appropriate times, a suitable brake mechanism (not shown) may be provided in the usual manner. Undesirable deflection of the reel and the shaft under the powerful strip tension forces usually employed is overcome by the provision of a retractable outboard bearing 17 (Fig. 1) that cooperates with a roller bearing 18 on the free end of the shaft 14.

The length of the reel is sufficient to accommodate winding thereon of strips of various widths, and the coils thus formed may be of various diameters, as indicated in Fig. 2, wherein a relatively narrow strip that winds up into a relatively large diameter coil is shown by the chain lines, while a coil of maximum width and of relatively small diameter is shown in full lines. The coil handing mechanism associated with the strip reel is designed to handle these coils of varying widths and diameters with equal facility and rapidity.

Disposed under the winding drum 13 in a suitable pit 19 is a reciprocable car 20 that carries all the mechanism for clamping and supporting the coil 12 when it is to be moved relative to the reel 13. The car is provided with flanged wheels 21, or suitable slides in lieu thereof, which are arranged to run on guide tracks 22, the path of movement of the car being parallel to the axis of the reel 13. Means are provided to move the car

from coil receiving position to coil unloading position as hereinafter described, but to move the car in the opposite direction a power cylinder 23 is provided. The piston working in this cylinder is connected through piston rod 24 to a bracket 25 depending from the underside of the car.

The car carries an upwardly movable coil support or elevator 26 which, as here shown, takes the form of a rectangular table or frame 27 that is secured to the upper end of a vertical plunger 28 that operates in a vertical cylinder 29 secured to the framework of the car. Vertical guide or brace rods 30 are secured at their upper ends to the table 27 and are slidably supported in bushed openings in the car's framework, the rods serving to brace the elevator against lateral deflection when raised and preventing undue wear between the plunger 28 and the cylinder wall. The lower ends of the rods 30 are provided with enlargements or washers 31 that serve as stops to limit vertical movement of the elevator past a predetermined point and, consequently, prevent complete movement of the plunger out of the cylinder. The vertical axis of the elevator and the cylinder 29 is aligned with the vertical diametral plane of the reel 13 and with the longitudinal center line of the mill rolls, the car always being returned to a normal position that locates the axis of the elevator in alignment with the mill's center line. To this end the cylinder 23 may be so located that the limit of retractive movement of its piston will be reached with the car in normal position, or, if desired, suitable stop blocks may be provided to engage with the car or its wheels to stop the car in its normal position.

Since it is intended in the embodiment of the invention herein illustrated that the elevator shall be raised into engagement with the strip metal coiling on the reel before completion of the coiling operation, and while the reel is rotating, coil engaging rollers 32 are provided on the elevator, and the periphery of these rolls is preferably of such material as rubber, fabric, or other fibrous materials as will not scratch or mar the surface finish of the strip metal. As shown more clearly in Fig. 4, a pair of such rollers is provided, the rollers being laterally spaced and arranged with their axes parallel to the axis of the reel so that the coil of strip metal will be cradled on the rollers and rotation of the coil with respect to the elevator permitted without damaging or scratching the strip metal. Each roller may be of any suitable construction and, as here shown, includes a supporting rod 33 fixed at its ends in plates 34 of the frame 27, on which rod a tube or sleeve 35 is rotatably supported by suitable bearings 36 at each end. The tube carries a spacing bushing 37 on either side of which is assembled a series of disc elements of suitable non-scratching material that are firmly held in compressed condition on the tube by compression members or nuts 38 in thread engagement with the threaded ends of the tube 35. Bushings 37 are of reduced diameter at their midportions to enable a tying wire or the like to be readily passed therebetween and the periphery of a coil when the rollers are in engagement with the coil, when desired.

Disposed in vertically opposed relation to the coil support 26 in overhanging relation to the reel 13 is a coil presser or holding device 39 that preferably includes a pair of rollers 40 similar to the rollers 32, and arranged in substantially the same manner for engaging the upper periphery of the coil. The rods 41 of these rollers are secured to a substantially H-shaped frame which, as shown

more clearly in Fig. 12, consists of end plates 42 welded or otherwise suitably secured to the ends of a channel member 43. The plates 42 are centrally pivoted on pins 44 in the bifurcated lower ends of hollow plungers or sleeves 45 that are slidably or telescopically received in vertical bores formed in the ends of a pivot block 46. Each plunger carries a central supporting rod 47 that extends upwardly through the top wall of the pivot block 46 on the outer end of which are provided adjusting and locking nuts 48. A compression spring 49 is provided for each plunger, the springs yieldably maintaining the H-frame and the rollers carried thereby downwardly in extended position relative to the pivot block 46, the extended position of the H-frame being adjustable by means of the nuts 48.

The pivot block 46 is disposed in a slot or eye formed in the free end of an arm 50 that is movable in a plane coinciding with the vertical diametral plane of the reel. A pivot bolt or pin 51 extends through the sides of the arm 50 and centrally through the block 46, whereby the block and the dependent structure it carries are substantially horizontally balanced on the pin 51. Likewise, the H-frame and the rollers carried thereby are disposed in balanced relation on the pins 44. It will be seen that since the axis 44 and the pin 51 are disposed in right angle relation, rocking movement of the rollers 40 transversely and longitudinally of the reel axis is provided, whereby the rollers 40 automatically accommodate themselves to the configuration of the coiling or completely coiled strip metal when the rollers are in engagement therewith. For example, in Fig. 12, the clamping position of the rollers with respect to the completed coil is illustrated, but when subjecting the incomplete coil to holding or clamping pressure while the tail end of the strip is still in the mill, the rollers 40 assume a tilted position, as will be apparent from an inspection of Fig. 3. End to end variation in the coil thickness may be accommodated by rocking of the rollers and block 50 on the pin 51.

The arm 50 adjacent the pin 51 is formed with reinforced wings 52 that bear against the sides of the pivot block 46 and firmly hold it against transverse twisting relative to the arm under the drag of the strip on the rollers 40.

At its other end, the arm 50 is provided with an integral hub portion formed with a crank arm 53 and an oppositely extending arm 54 on which a counterbalancing weight 55 is adjustably carried. The hub of the arm is supported on a shaft 56 that is journalled in suitable bearings in the upper end of an upright support or standard 57 that is rigidly connected to the car 20 at the front end thereof, that is, adjacent the free end of the reel 13. The standard 57 may suitably be formed as an integral part of the car structure. As shown more clearly in Fig. 3, the standard 57 is offset to one side (mill side) of the axis of the mandrel 13 and is provided with a straight edge 58 along its inner side, which may serve as a gauge stop for a swinging coil gate 59 to be hereinafter described.

Pivotedly connected to the crank arm 53 is an adjustable connecting rod 60 whose lower end is pivotally connected at 61 to one end of a lever 62 which is supported on a shaft 63. Links 64 are secured to the ends of the shaft 63 and these links are rockingly supported on a shaft 65, as best seen in Fig. 5, which is supported at its ends in bracket plates 66 that are secured to or

formed as an integral part of the car framework. The other end of the lever 62 is forked and straddles the vertically movable platform 26, and the respective arms of the fork are journalled on trunnions 67 projecting laterally from the sides of the movable platform. This arrangement utilizes the vertical cylinder 29 and its plunger 28 as the prime mover for actuating the lever 62, and it will be seen that the rod 60 is connected to the lever 62 and arm 50 in such a manner that the coil support or movable platform 26 and the coil holding device 39 are moved in opposite directions and preferably through equal distances. Consequently, when fluid pressure is admitted to the lower end of the cylinder 29, the coil support is moved upwardly to bring its rollers 32 into engagement with the underside of the coil 12, and the coil holding device 39 is moved downwardly and the upper side of the coil engaged by the rollers 40 thereof, the links 64 enabling the lever 62 to shift lengthwise and accommodate itself to the straight line movements of the trunnions 67.

However, for reasons as will hereinafter appear, the strip engaging rollers 40 are normally positioned in advance of or closer to the axis of the reel than the rollers 32 when the arm 50 and lever 62 are in raised and lowered positions, respectively.

As shown in Figs. 2 and 7, the hydraulic mechanism for actuating the elevator 26 is carried by the car 20 and includes a tank or reservoir 68, a pump 69 driven by an electric motor 70, a pressure relief valve 71, and a pair of normally spring closed, solenoid operated control valves 72 and 73. Valve 72, when its solenoid is energized, admits fluid pressure from the pump 69 to the vertical cylinder 29 through the conduit 74, to raise the elevator 26, while valve 73, when its solenoid is energized, permits the fluid in the cylinder 29 to exhaust through conduit 74, past the open valve 73, and drain to the tank 68 to lower the elevator 26. Push button switches 75 and 76 are provided at a suitable remote control station conveniently located for the operator for connecting the respective solenoids of the control valves to a suitable source of electric power. The pump is provided with the usual pressure relief by-pass so that it may be continuously driven by the motor 70 without breakdown during the periods that the valve 72 is in closed position. The pressure relief valve 71 is connected to the conduit 74 and operates to bleed the pressure in the conduit when the pressure conditions therein exceed the pressure for which valve 71 is adjusted. The valve is adjusted in conformity with the weight of the coil to sustain a pressure that is but slightly greater than the pressure required to support the coil on the elevator, and when coils of different weights are being handled, the valve may be adjusted accordingly in order to eliminate subjecting the reel to uncontrolled and excessive elevator forces. All the foregoing hydraulic mechanism is mounted upon the car so that it is only necessary to provide a flexible cable containing the power lines for the motor 70 and the control wires for the solenoids 72 and 73. This arrangement eliminates the need for using high pressure hydraulic lines running to the car and the necessary slip joints therefor which are usually subject to considerable leakage and require constant maintenance.

Heretofore it has been customary in coiling resilient and work hardened strip metal under

tension on a reel to complete the coiling operation, stop the reel, and then tie the coil to prevent looseness developing in the coil by unwinding of the strip, all prior to stripping of the tied coil from the roll. In this practice, winding mechanism provided with external strip confining cage sections, strip holding belts, or other devices have been employed to confine the trailing end of the strip as it leaves the rolling mill or other strip processing mechanism, and to hold the coil against unwinding prior to tying, after which the confining structures are required to be moved to non-interfering positions relative to the tied coil and stripper mechanism, and the stripper mechanism then actuated to push the coil off the end of the reel. It is apparent, of course, that the principal strip processing equipment with which the reel structure is associated cannot be used productively until completion of the unloading operation and return of the stripper mechanism to retracted position. Consequently, it is desirable that the reel mechanism be unloaded and made available for re-reeling as quickly as possible, consistent with careful handling of the coil so as not to mar or scratch the metal surfaces, particularly when at final stages of metal processing the surfaces are highly finished.

These results are attained by the instant invention in the following manner. Referring to Fig. 7, behind the reel 13, aligned with the rolling mill 10, is a belt wrapper 77 that is mounted upon a car 78 for movement into and out of cooperative relation with the reel, the car being mounted on suitable tracks and movable therealong by a hydraulic cylinder 79. This belt wrapper is used to initiate winding of the strip 11 around the reel block 13 and is retracted or moved out of wrapping position as soon as several wraps of the strip have been wound on the reel. The normal raised and lowered positions of the rollers 40 and 32 with the car in normal position afford sufficient clearance for operation of the belt wrapper. Thereafter, as coiling of the strip proceeds, the operator watches for the approach of the end of the strip to the mill rolls, whereupon he depresses the push button 75, the valve 72 opens by energization of its solenoid, and fluid pressure from the pump 69 is admitted to the elevating cylinder 29. As the elevator 26 moves upwardly, the holding device 39 moves downwardly, and since the rollers 40 are in advance of the rollers 32, they engage the upper periphery of the coil, and continued movement of the elevator toward the coil causes telescoping movement of the sleeves 45 in the block 46 with further compression of the springs 49, whereupon the rollers 40 are forced to bear against the upper side of the strip with a firm clamping pressure under pressure of the springs 49. When the rollers 32 of the elevator engage or are about to engage the underside of the coil, the switch 75 is released, whereupon the valve 72 closes and traps the liquid in the cylinder 29, thus locking the cylinder in its coil supporting position. During lowering movement of the arm 50, the H-frame rocks on the pins 44 to a tilted position by reason of one roller 40 engaging the taut tangent portion of the incoming strip while the other roller engages the coiled portion of the strip on the other side of the vertical plane of the coil.

Thereafter, as the rear end of the strip leaves the mill rolls, the loss of tension in the strip permits the roller frame to swing to horizontal position, as shown in Fig. 12, and winding of the

tail of the strip is completed while the coil is thus firmly held so that no looseness can develop in the coil and the tail is held against whipping or flapping about wildly until rotation of the reel 5 is stopped in the usual way. Immediately, the reel is collapsed and the weight of the coil is thereby transferred to the coil support 26. If the reel is of the eccentric collapsible type, it is preferred to stop the same with its radially movable segment down so that after the reel is collapsed the coil support and the coil thereon may be moved upwardly a slight distance by momentarily depressing the switch 75 to raise the coil relative to the reel and effect substantially uniform clearance between the inside surface of the coil and the periphery of the reel. However, by reason of the manner of stripping the clamped coil, as hereinafter described, it is not essential that such upward movement be imparted to the coil. 10 At no time is the coil free of the clamping or holding force imposed thereon by the spring pressed rollers 40 so that unwinding of the strip and looseness developing in the coil is effectively prevented. Hence, the coil supported and 15 clamped between the opposed coil engaging members may be stripped or unloaded from the reel without delaying to tie the coil.

Stripping is effected by moving the car to the right, as viewed in Fig. 2, but in order to prevent 20 possibility of the inner turns of the coil telescoping by frictional engagement with any part of the reel 13, a stripper 81 which encircles the lower semi-circumference of the reel is provided, the stripper being first moved into engagement 25 with the adjacent end of the coil, and thereafter unitary traveling movement being imparted to the stripper and the car. Normally, the stripper is held in a retracted position adjacent the supported end of the reel so as not to interfere with 30 winding of the strip and is moved along the reel by a traversing cylinder 82 (Fig. 2) whose piston is connected to piston rod 83 that is connected to the stripper. Rearwardly extending rods 84 (Figs. 8 and 9) secured to the stripper and slidably supported in the frame 16 are provided to 35 guide the stripper. The stripper is supported on feet or slide shoes 85 that are slidable along supporting rails 86 that are suitably supported along the sides of the pit 19. At diametrically opposite 40 sides of the reel, the stripper is provided with blocks 87 that are spring pressed against the sides of the reel, the blocks being flush with the coil engaging face of the stripper and serving to 45 engage the innermost coil turns and prevent telescoping thereof.

Below one of the blocks 87, a wide faced plunger 88 is provided and projects forwardly of the face of the stripper to engage the end of the coil ahead of the stripper. The plunger extends through 50 the stripper and is secured to the upper end of a rocker arm 89 that is secured intermediate its ends to a shaft 90 journalled in bearing bosses on the rear side of the stripper. The lower end of the rocker arm is biased rearwardly by springs 91. Below the arm 89, a shaft 92 is journalled in spaced bearing bosses suitably secured or integral with the stripper. The shaft 92 carries a pair of dogs 93 and 94 extending upwardly behind the rocker arm and a pair of forwardly extending pawls 95 and 96 which are provided to 55 cooperate with rack bars 97 and 98 carried by the car 20. Dog 94 and pawl 95 are secured to a sleeve 99 loosely mounted on the shaft 92 for rotary movement independently of the dog 93 and pawl 96 which are fixed to the shaft. Normally 60

springs 91 hold the arm 89 and the dogs 93 and 94 back far enough to maintain the pawls disengaged from the rack bars. One rack bar is mounted on the car with its teeth opposite the tooth spaces of the other rack bar, as shown more clearly in Fig. 11, so that when the pawls drop, the one pawl may move into a tooth space of its associate rack even though the other pawl drops onto the top of a tooth on its associate rack and, at least, thereby minimize relative longitudinal travel between the pawls and the rack bars in establishing effective engagement between one pawl and one rack. The pawls and racks are of rather heavy construction since the car is to be moved in one direction thereby. Leaf springs 100 carried by the arms 89 bias the dogs 93 and 94 against the rear side of the arm 89.

Following clamping and supporting of the coil in the above described manner, fluid pressure is admitted to the rear end of the stripper cylinder 82 from a motor driven pump 101 (Fig. 7) through a three-way valve 102, thereby moving the stripper 81 along the collapsed mandrel and relative to the car (since the pawls 95 and 96 are raised) into engagement with the adjacent end of the coil. Depression of the plunger 88 through its contacting the end of the coil rocks the lower end of the arm 89 away from the dogs 93 and 94, thereby allowing the pawls 95 and 96 to drop onto the rack bars, one pawl moving into effective engagement with its rack substantially in synchronism with the initial contact of the face of the stripper with the end of the coil. As this inter-engagement between the stripper and the car is established automatically, the stripper movement is continuous and thereafter the car and the stripper move in unison, during which movement the stripper bears against all the turns of the coil so that axial telescoping of the coil is prevented.

As the coil leaves the end of the mandrel 13, it encircles and moves along the coil gate 59 which comprises a horizontal beam 103 supported at one end on an upright shaft 104 for swinging movement, the beam normally being disposed in coil receiving position in longitudinal alignment with the axis of the mandrel. A straight edge 105 is secured to one side of the beam 103 for cooperating with the gauge stop 58 of the car upright 57, thus enabling accurate positioning of the beam in aligned relation with the reel. A series of coil supporting rollers 106 are provided along both sides of the beam, which rollers are mounted on rods 107 carried by the beam, and project above the upper edge of the beam, the peripheries of the rollers being tapered along curved lines corresponding substantially to the curvature of the innermost turn of the coil so as to have adequate bearing contact therewith when the coil is lowered into engagement with the rollers. The upright shaft 104 is carried by a pedestal base 108 that spans the pit 19 and is suitably anchored to the mill floor, as best seen in Fig. 6, the pedestal being located beyond the outer limit of car travel. Covering the pit between the car and the pedestal is a movable floor section 109 that is secured at one end to the car 20 (Fig. 2) and is slidably supported on lateral rails 110 for movement under the pedestal when the car is advanced.

Traveling movement of the car and the stripper is automatically terminated when the coil has been moved entirely clear of the mandrel into substantially the position shown by the broken lines in Fig. 2, by operation of a normally closed limit switch 111 (Fig. 7) which is positioned to be

actuated by the stripper or the car. In response to actuation of the switch 111, the stripper is automatically returned immediately to its normal position independently of return of the car, thereby conditioning the reeling equipment for receiving the succeeding strip. This mode of operation will now be described with reference to the control system shown in Fig. 7.

High pressure and return hydraulic lines are indicated by the numerals 112 and 113, respectively, the former being continuously supplied with fluid under pressure from pump 101, excess pressure being bled from the line by a pressure relief valve 114. The piston rod end of the stripper per cylinder 82 is connected directly to the line 112 by branch pipe 115, which pipe also is connected to the normally closed inlet or pressure port of valve 102 through check valve 116. The exhaust port of valve 102 is connected through check valve 117 to the return line 113 and is normally open to the outlet port of valve 102, which valve is connected to the other end of cylinder 82 by pipe 118. When valve 102 is actuated, communication is established between its pressure and outlet ports and its exhaust port is closed, whereby fluid pressure is admitted through pipe 118 to the rear end of cylinder 82 and the piston therein advanced under the pressure differential at its opposite sides. It will be seen that with these connections and with valve 102 in normal position, the stripper 81 is held in normal retracted position by the constantly applied fluid pressure, and that upon advance movement of the stripper by actuation of the valve the stripper will be retracted automatically whenever the valve 102 is restored to normal position. The belt wrapper cylinder 79 is connected to the hydraulic lines 112 and 113, and controlled in the same manner, and the same numerals primed have been applied to the corresponding valves and pipe connections.

The valves 102 and 102' are electrically controlled and may be of any suitable type. The type shown are known as thruster operated valves wherein an impeller pump 119 driven by a motor 120 supplies a low pressure fluid for raising the movable element of the valve, which element drops by gravity or under light spring pressure to normal position when the impeller motor is de-energized. Also, the carriage cylinder 23 is provided with a three-way valve 121, but this valve is manually actuated, and its pressure and exhaust ports are connected to the lines 112 and 113, respectively, through check valves 122 and 123. Its outlet port, which in normal position of the valve is in communication with the exhaust port, is connected to the front end of the cylinder 23 by pipe 124, the rear end of the cylinder being directly connected to the drain line 113. A check valve 125 (the direction of flow permitted by the check valves being indicated by arrows) is connected in the pipe 124, and an adjustable valve 126 by-passes the check valve 125 and serves to regulate the rate of return movement of the car 20 when the valve 121 is actuated to admit fluid pressure to the pipe 124.

The stripper 81 and the belt wrapper 79 are electrically interlocked so as to prevent operation of either one when the other is out of its normal retracted position. The interlock includes normally open limit switches 127 and 128 in the control circuits for the valves 102 and 102', switch 127 being held in closed position by the belt wrapper in its retracted position, and switch 128

being held closed by the stripper in its retracted position. In Fig. 7, the belt wrapper 77 is shown in wrapping position. Hence, the stripper cannot be actuated since the limit switch 121 through which the control circuit for the valve 102 extends is open. It will be recalled that the belt wrapper is used but a short time at the beginning of the coiling operation, movement of the belt wrapper being effected manually by closure of a switch W which energizes the motor 120', thereby causing the valve 102' to be actuated and admit fluid pressure through the pipe 118' to the rear end of the belt wrapper cylinder. The electrical energy for energizing the motor is supplied from lines L1 and L2 of a three-phase current supply. It will be seen that the circuit for the motor 120' extends through the switch 128 which is now in closed position due to retraction of the stripper, but that if the stripper should be accidentally moved, the circuit would be broken by operation of the limit switch and the belt wrapper automatically moved to its retracted position by movement of valve 102' to normal position so that the constantly applied pressure to the front end of the cylinder 79 would be effective to move the piston therein rearwardly. When the belt wrapper has completed its function normally, it is automatically returned to retracted position by releasing the push button switch W and the switch 121 is closed thereby.

Thereafter, the automatic cycle of coil stripping movement can be initiated, subsequent to operation of the opposed coil clamping and supporting members in the manner heretofore described, by depression of a push button switch S which energizes a control relay 129 through a circuit extending from line L1, contacts of switch S, winding of relay 129, conductor 130, closed contacts of switch 127, and conductor 131 to line L2. Relay 129 is maintained in closed position by a holding circuit which it completes for itself at contacts 132, and at contacts 133, completes the energizing circuit for the impeller motor 120 of the valve 102. The motor energizing circuit extends from L1, contacts 133, conductor 134, motor 120, conductor 135, and conductor 131 to L2. The holding circuit extends from line L1, conductor 136, contacts of the normally closed limit switch 111, contacts 132, winding of relay 129, and through the interlock switch 127 to line L2 by way of conductors 130 and 131. This holding circuit merely shunts the switch S and the switch may be released by the operator. The valve 102 is thus moved to and maintained in operative position so long as the relay 129 is held energized to maintain the circuit for the motor 120.

Operation of valve 102 in this manner permits flow of pressure fluid from line 112 to the rear end of the cylinder 82, the fluid in front of the piston in said cylinder being displaced and forced through pipe 115 where it flows to the rear side of the piston with the fluid from the line 112, whereby the stripper is advanced to move the coil 12 and the car 20 in the manner heretofore described. During advance movement of the car 20, the fluid in front of the piston in the car retracting cylinder 23 exhausts through the pipe 124 past check valve 125, valve 121, and check valve 123 to the drain line 113. The unitary traveling movement of the stripper and the car automatically terminates when the limit switch 111 is opened, as heretofore mentioned, which results in opening the holding circuit for the relay 129 and it de-energizes and

5 opens the circuit for the motor 120. Consequently, the valve 102 drops to its normal position and interrupts flow of pressure through pipe 118 and connects this pipe to the exhaust line, whereupon the stripper immediately begins its retractive movement by the constantly applied pressure to the front end of the stripper cylinder, thus leaving the clamped coil and the car in unloading position at the coil gate. During 10 initial movement of the stripper away from the coil, the pawls 95 and 96 merely ratchet with respect to the rack bars until the plunger 88 becomes fully extended, whereupon the springs 91 15 rock the arm 89 so that the dogs 93 and 94 are turned backwardly and the pawls 95 and 96 lifted out of engagement with the rack bars. Upon reaching its normal retracted position, the stripper closes the switch 128, thus conditioning the control apparatus for operation of the belt wrapper and enabling the reel to receive a succeeding strip.

20 During coiling of the succeeding strip, the preceding coil at the coil gate is tied so as to hold it in tight wound condition and then transferred or lowered onto the coil gate. The coil is released by depression of switch 76 which actuates valve 73 and allows fluid in cylinder 29 to exhaust to the tank 68, whereupon the elevator 26 is lowered and the coil clamping device 39 25 moved upwardly to their respective normal positions, after which the switch 76 is released. The coil gate is then swung into alignment with a suitable coil receiving conveyor, storage platform, or the like and the tied coil 12 pushed off the coil gate onto the conveyor, storage platform, or the like. After the coil is thus removed from the coil gate, the gate is returned to normal position in alignment with the reel; and the car 20 is then or previously returned to 30 its normal position under the reel by manually actuating the valve 121 which admits fluid pressure to the front end of the cylinder 23, the carriage stopping in its normal position in the manner heretofore described.

35 40 From the foregoing, it will be seen that the operations of tying the coil, unloading the tied coil from the coil gate and return of the car are performed during coiling of the succeeding strip, and that rough handling of the coil throughout 45 the entire unloading operation is eliminated. It has been found that with this mode of operation which is effective with all kinds of strip metal, a material saving in unloading time has been 50 accomplished which has resulted in a greater output 55 by the processing equipment for a given period of time or day's operation.

55 By reason of the rotatable support afforded the coil by the sets of rollers 40 and 32, the foregoing apparatus may also be employed to deliver 60 the tightly wound coils to an unwinding block and permit the coil to be rotated while still clamped so as to be entered into a rolling mill and the coil thereafter released, thereby preventing looseness developing in the coil during the 65 initial stages of a feeding operation when the coil is untied and a sufficient length of strip is uncoiled for entry into a mill.

65 It is to be understood that various changes and modifications may be made in the foregoing apparatus and construction of the parts thereof, and substitutions of equivalent mechanism effected without departing from the spirit of the invention and the scope of the appended claims.

70 What is claimed is:

75 1. In a coil handling apparatus of the class

described, a pair of vertically opposed coil engaging elements movable into and out of peripheral contact with a coil disposed therebetween, a horizontally movable frame structure carrying said elements, means on said frame structure for actuating said coil engaging elements, to support and clamp the coil thereby, and means for moving said frame structure to move the coil from one axial coil support to another.

2. A coil handling apparatus of the class described, comprising a pair of vertically opposed members movable toward and away from each other, into and out of engagement with the periphery of a coil disposed therebetween, rotatable means on the opposed faces of said members for engaging the periphery of said coil, a horizontally movable frame structure carrying said members, means on said structure for moving said members toward each other, whereby to rotatably clamp and support the coil, and means for imparting traveling movement to said frame structure to transfer the coil from one axial coil support to another.

3. In a coil handling apparatus of the class described, a pair of vertically opposed coil engaging devices, operating means for said devices for moving them into peripheral engagement with a coil forming therebetween, means for supporting each of said devices for movement in a direction parallel to the axis of the coil and means for moving said devices in said direction while in engagement with said coil.

4. A coil handling apparatus of the class described, comprising a pair of vertically opposed members movable toward and away from the periphery of a coil rotatably supported therebetween, rotatable means on the opposed faces of said members for engaging the periphery of said coil, a horizontally movable frame structure carrying said members, means on said structure for moving said members toward each other, whereby to rotatably clamp and support the coil, and means for imparting traveling movement to said frame structure to transfer the coil from one axial coil support to another, said rotatable means on the upper opposed member being resiliently mounted thereon for vertical movement with respect thereto and being disposed in position to engage the upper side of said coil before said rotatable means on the lower member engages the underside of the coil.

5. In a coil handling apparatus of the class described, an upwardly movable coil support, a reciprocable carriage on which said support is mounted, means on the carriage for actuating said coil support into supporting engagement with the lower periphery of coiled strip material, a presser member mounted on the carriage in position to engage the periphery of the coil at a point upwardly removed from said support, and means for actuating said presser member into said engaging position prior to completion of the coiling operation.

6. In a coil handling apparatus of the class described, an upwardly movable coil support, a reciprocable carriage on which said support is mounted, means on the carriage for actuating said coil support into supporting engagement with the lower periphery of coiled strip material, a presser member mounted on the carriage in position overhanging said support and the coil engaged thereby, and means operatively connecting said support with said presser member to move the latter downwardly into holding engage-

ment with the coil upon upward movement of said coil support.

7. In a coil handling apparatus of the class described, an upwardly movable coil support, a reciprocable carriage on which said support is mounted, means on the carriage for actuating said coil support into supporting engagement with the lower periphery of coiled strip material, a presser member mounted on the carriage in position overhanging said support and the coil engaged thereby, means operatively connecting said support with said presser member to move the latter downwardly into holding engagement with the coil upon upward movement of said coil support, and means normally yieldably maintaining said presser member in position to engage the upper periphery of the coil prior to engagement of said support with the lower periphery of the coil.

8. Unloading apparatus for a strip coiler having a collapsible mandrel on which strip material is wound into a coil, comprising, in combination, a stripper movable along the mandrel to strip the coil therefrom, means for moving the stripper, a carriage adjacent the mandrel, guide means for the carriage paralleling the axis of the mandrel, means on the carriage for supporting and clamping the coil prior to and during stripping thereof off the collapsed mandrel, means for imparting unitary traveling movement to the stripper and the carriage after the end of the coil is engaged by the stripper, and means operative to return the stripper independently of return movement of the carriage.

9. Unloading apparatus for a strip coiler having a collapsible mandrel on which strip material is wound into a coil, comprising in combination, a stripper movable along the mandrel to strip the coil therefrom, a carriage under the mandrel and movable parallel to the axis thereof, means on the carriage movable into engagement with the upper and lower periphery of the coil on the mandrel for supporting and clamping the coil prior to and during stripping thereof off the collapsed mandrel, means for connecting the stripper and carriage for unitary movement in a direction to strip the coil from the mandrel, means actuated by engagement of the stripper with the adjacent end of the coil for actuating said connecting means, whereby the carriage and the coil are moved by the stripper to a position beyond the free end of the mandrel, and means actuated in response to movement of the coil to said position for automatically returning the stripper independently of return movement of the carriage.

10. Unloading apparatus for a strip coiler having a collapsible mandrel on which strip material is wound into a coil, comprising, in combination, a carriage under the mandrel and movable parallel to the axis thereof, vertically opposed means on the carriage movable into clamping and supporting engagement with the periphery of a coil on the mandrel, means on the carriage for actuating said opposed means into supporting and clamping engagement with the coil for unloading movement, a stripper cooperating with the mandrel and disposed rearwardly of said carriage, means for moving the stripper relative to the carriage into engagement with the adjacent end of the coil to impart unloading movement thereto, a rack on the carriage, a latching member carried by said stripper for cooperating with said rack and normally disconnected therefrom to permit free movement of the stripper relative to the carriage until the stripper engages the end

of the coil, a projecting plunger on the coil engaging face of the stripper, and means actuated by said plunger for moving said latch member into engagement with said rack whereby said carriage and the coil are moved by continued movement of the stripper to a position beyond the end of the mandrel.

11. In combination, a coiling mechanism having an expansible and collapsible winding drum and means for rotating the same, a swingable coil gate disposed in horizontal alignment with the axis of the drum to receive a coil stripped therefrom, a carriage movable between said drum and said gate in a path located therebelow, vertically opposed devices, including coil engaging rollers, mounted on the carriage and normally disposed in spaced relation to the upper and lower periphery of the coil of strip material being wound on the drum, means for moving said opposed means toward the axis of said drum to engage the periphery of the strip material being wound thereon with said rollers as the end of the strip approaches the coiler mechanism, the coil being supported on the rollers engaging its lower periphery when the drum is collapsed, and a stripper movable along the drum and arranged to engage the adjacent end of the coil and the carriage and simultaneously move them into unloading position at said coil gate.

12. In combination, a coiling mechanism having an expansible and collapsible winding drum and means for rotating the same, a swingable coil gate disposed in horizontal alignment with the axis of the drum to receive a coil stripped therefrom, a carriage movable between said drum and said gate in a path located therebelow, an upwardly movable coil support on the carriage for supporting the completed coil when the drum is collapsed, a spring pressed roller above the drum opposite said coil support and movable downwardly into engagement with the upper periphery of the coil as the end of the strip approaches the coiler, a laterally disposed upright on the forward end of the carriage, a supporting member mounted on said upright for movements in a vertical plane on which said pressure roller is mounted, means on the carriage for simultaneously moving the coil support upwardly and the pressure roller downwardly to support and clamp the coil therebetween, said coil support including rollers for rotatably supporting the coil, and means for moving the carriage from its position under the winding drum to its position under said coil gate.

5 13. A strip handling apparatus comprising a rotatable reel on which the strip material is wound into a coil, a coil support movable upwardly into supporting engagement with the coil on said reel, a coil clamping member movable downwardly into clamping engagement with the coil forming on the reel, and means for moving said support and said clamping member axially of said reel in unison to remove the coil therefrom.

10 14. A strip handling apparatus comprising a rotatable reel on which the strip material is wound into a coil, a coil support under the reel and movable upwardly into supporting engagement with the coil on said reel, a coil clamping member above the reel opposite the coil support and movable downwardly into clamping engagement with the coil forming on the reel, and means for moving said support and said clamping member axially of said reel in unison to remove the coil therefrom, said coil support and said clamping member being retractable into said under and over positions, respectively, relative to the reel during winding of a succeeding strip of material on the reel.

15 15. Handling means for coiled strip metal that requires tying to maintain the strip in tight wound condition comprising in combination, a collapsible reel on which the strip is wound into a coil, a swinging arm normally disposed in axial alignment with said reel to afford interior support to the coil when stripped from said reel, vertically opposed devices including rollers mounted for movement into supporting and clamping engagement with the exterior periphery of the coil forming on said reel, means for actuating said opposed devices, and means for moving said opposed devices simultaneously while in clamping and supporting engagement with the completed coil in a direction to carry the coil from the reel to said swinging arm.

20 16. In a coil handling apparatus of the type described, a pair of vertically opposed devices including rollers movable into and out of peripheral contact with a coil disposed therebetween, a reciprocable car carrying said devices, hydraulic means and electrically actuated control devices therefor entirely mounted on the car for effecting said movements of said coil engaging devices, and electrical means for actuating said control devices from a point remote from said car.

EDWARD M. CHANDLER.
